(57) **CLAIM**

I claim the ornamental design for an armored backpack, as shown and described.

DESCRIPTION

FIG. 1 is a front perspective view of an armored backpack, showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a rear elevational view thereof;

FIG. 7 is a top plan view thereof; and,

FIG. 8 is a bottom plan view thereof.

The broken lines showing a logo panel in FIGS. 2 and 4 depict portions of the backpack that form no part of the claimed design. The remaining broken lines in the figures represent stitching, and are part of the claimed design.
